COMBINED TOOTHBRUSH AND PASTE HOLDER AND CUP DISPENSING UNIT

Vincent E. Gardner, Wayne, Mich., assignor to Marilyn Sue Powers, Allen Park, Mich.

Filed Apr. 12, 1967, Ser. No. 6,647

Term of patent 14 years

(Cl. D33—26)

FIG.1

The broken line representation of a toothpaste tube and toothbrushes in FIGURE 1 and of a cup in FIGURES 2, 3 and 4 is for purposes of illustration only.

I claim:

The ornamental design for a combined toothbrush and paste holder and cup dispensing unit, substantially as shown and described.
